UNITED STATES PATENT OFFICE.

GEORGE P. KREHBIEL, OF PASSAIC, NEW JERSEY.

CLIP OR PAPER FASTENER.

Application filed August 29, 1921. Serial No. 496,344.

To all whom it may concern:

Be it known that I, GEORGE P. KREHBIEL, a citizen of the United States of America, residing at Passaic, in the county 5 of Passaic and State of New Jersey, have invented certain new and useful improvements in clips or paper fasteners for securing sheets of paper, etc., temporarily into bundle or book form in such manner that 10 one or more sheets may be easily and quickly removed or new ones inserted without disturbance of the remaining sheets.

My said invention relates to the particular form of such clips commonly known as 15 the "McGill clip," which are formed of thin sheet metal, usually brass, having a base or head portion from which project at right angles two penetrating standards or securing-members, easily passed thru the sheets 20 to be secured together into a bundle; when only a few sheets are to be so bound being themselves forced thru the sheets, and when a large and thick body of leaves is to be so bound, such hole for the passage of such securing-member or standard, being first 25 formed at the proper point thru all the sheets, by a suitable punch, or bodkin like pointed tool, etc., after which, the projecting ends of the standards or securing-members 30 on the side of the bundle opposite to that on which is the head of the clip, are forced tightly down upon the bundle on that side, one in one direction and the other in the opposite direction, to hold all the 35 sheets tightly bound together.

My said new and improved form of such clip, herein first disclosed differs from those hitherto known in the prior art, in that the head or base portion, and the two securing- 40 members are formed integrally of a single piece of thin sheet-metal blanked into proper form, and then bent up, and rolled, swaged or pressed into a perfect clip ready to be passed thru a bundle of sheets, and 45 have its securing-members forced in opposite directions down upon the adjacent face of the bundle, so as to bind all the sheets between such bent down ends, and the integral base-portion or head of the clip in the well known manner. So far such description of the device and its operation will apply in a measure at least to all clips of the "McGill type," but my said improved clip herein first shown differs from all such prior 50 devices, in that one of the securing standards or members is central to the other co-

acting like securing-member and is slightly shorter than the outer member, with which it is integrally formed, in such manner as to leave such outer member, when the two 60 are bent down upon the bundle of sheets secured thereby, in opposite directions, with a central elongated slot of the size and contour of the central or tongue-member, which slot is usually and preferably but not 65 necessarily closed at the outer and free end.

My said new and improved clip, is fully shown and described in the following specification of which the accompanying drawing 70 forms a part, wherein similar numerals of reference designate like or equivalent parts wherever found thruout the several views, and in which:

Figure 1, is a top view from the front 75 and side, in perspective, of my improved clip;

Fig. 2, is a side edge view thereof taken in central vertical section on the line 2—2 of Fig. 1, looking in the direction of the 80 arrows;

Fig. 3, is a view similar to that shown in Fig. 2, taken on the same sectional line showing the same as it appears when the securing standards or members are bent into 85 the sheet bundle binding and securing position;

Fig. 4, is a view of the clip inverted and supported upon its head;

Fig. 5, is a view thereof in section on the 90 line 5—5, of Fig. 2, looking toward the right in the direction of the arrows; and

Fig. 6, is a face view of the blank of sheet-metal out of which the clip is bent, rolled, and swaged into form. 95

Referring to the drawings—

To form my improved clip, as shown in Fig. 6, by the use of a suitable blank forming punching and slitting die, blanks of the shape and contour desired are formed having the outer head or base-portion 1 circular in form, joined to the inner base-plate 2, as indicated at 3; which base-plate 2, is slightly smaller than 1, as to diameter, and is provided opposite to 3, with the outer 100 slotted standard or securing-member 4, and the inner central tongue standard or securing-member 5, both of which members 4, and 5, have their bases substantially coincident with the central portion of the base-plate 2, whereby when the clip is fully formed such base-plate 2, will be provided 105 110

on one side with the slot 6 (Figs. 2, 3, and 4,) of the width of the outer standard 4.

Such blanks in commercial manufacture, are then fed one by one to a suitable forming machine, of the form well known in the art, but slightly modified to suit the exigencies of this particular clip, and which are of the well known automatic form; wherein the outer head or base-portion 1, is swaged or 10 spun down over the inner base-plate 2, so as to enclose the same at the peripheral edge, (Figs. 2, 3, 4 and 5, at 7) and at the same time the metal at the juncture 3, of the blank as to the base-plate 2, is forced inward and outward, as clearly indicated at 15 8, (Figs. 2, 3 and 4) in such manner as to force the metal of the outer face of the base-plate 2, thruout the juncture, (from 9 to 9', of Fig. 4) into the form of an outwardly 20 rounded roll.

Many changes may be made in the construction of my improved clip, such for instance as omitting the closed end bar 4', of the outer standard or securing-member 4, 25 and extending the tongue member 5, the full length of the slot of 4, may be made without in any manner departing from the broad scope of my invention, and I do not in any manner intend to limit myself to the 30 exact form.

I claim:

A clip or paper-fastener of the class described, comprising a double-walled head or 35 securing base-portion, having an inner or lower, and an outer or upper, substantially circular plate, superposed one upon the other, the outer or upper plate being of slightly larger diameter than is the inner or low-

er like smaller diametered plate formed integral therewith and connected thereto along 40 a short portion of the peripheral edge of each of such plates; the outer or upper larger diametered circular plate being bent over and superposed upon the top surface of the inner lower smaller diametered like plate, 45 and having its bounding outer peripheral edge swaged down over upon and around the peripheral bounding-edge of such inner or lower integral circular smaller diametered plate, in such manner as to secure the two 50 plates together so as to form a single integral head or securing base-portion double-walled and of dome-like and rounded contour; and a double-tongued longitudinally centrally slotted securing-member formed 55 integral with the inner or lower circular smaller diametered plate extending outward therefrom at substantially a right angle to the plane of such inner or lower plate; the construction being such that the single central tongue lies normally in the slot of its coacting securing-member, so that both the 60 securing-members are simultaneously passed thru the bundle of sheets etc., to be secured, after which the central solid-tongue is bent to one side down into contact with the bundle of sheets adjacent to the head-in one direction and the centrally slotted securing-member or tongue bent down into like contact with the bundle of sheets adjacent to the 65 head, in the opposite direction.

Signed at the borough of Manhattan, county, city, and State of New York, this 26th day of July, 1921.

GEORGE P. KREHBIEL.
